UNITED STATES PATENT OFFICE.

HARRY EXETER BEASLEY AND WALTER BYRD, OF VICTORIA, BRITISH COLUMBIA,
CANADA.

DIRIGIBLE HEADLIGHT.

1,425,439.

Specification of Letters Patent. Patented Aug. 8, 1922.

Application filed May 10, 1921. Serial No. 468,442.

To all whom it may concern:

Be it known that we, HARRY E. BEASLEY and WALTER BYRD, both subjects of the King of England, and residents of Victoria, B. C., 5 Canada, have invented a new and Improved Dirigible Headlight, of which the following is a full, clear, and exact description.

Our invention relates to certain new and useful improvements in dirigible headlights, 10 and is more particularly predicated to improvements in structure over our prior Patent 1,204,930 dated November 14, 1916.

It has been found with regards to this prior patent that the controller may be improved, to simplify the construction of the 15 same, and also to insure a more efficient operation thereof, so that the device is rendered more attractive from a commercial standpoint, in that the cost of manufacture 20 is reduced, a positive operation assured, and that the application of the device to a vehicle such as a locomotive is simplified.

Furthermore, the present invention aims to provide certain improvements in connection 25 with the actuating mechanism for the lamp, and which will further insure the efficiency of operation.

Still further objects of our invention will become apparent from the attached specification taken in connection with the drawings, which latter present one practical embodiment of the same, and in which;

Figure 1 is a partly fragmentary side view of the front end of a locomotive showing our 35 device associated therewith.

Figure 2 is a front view of the same.

Figure 3 is a sectional plan view taken along the line 3—3 and in the direction of the arrows indicated in Figure 2.

40 Figure 4 is a sectional side view taken along the line 4—4 and in the direction of the arrows indicated in Figure 1, and

Figure 5 is a similar sectional view taken along the line 5—5 and in the direction of 45 the arrows indicated in Figure 3.

Our invention is primarily intended for use in connection with a locomotive headlight, and thus in the embodiment illustrated, we have shown the same associated with 50 a device of this nature.

Referring now more particularly to Figures 1 and 2 it will be seen that the reference numeral 10 indicates the boiler of a locomotive which, in the usual manner mounts, 55 adjacent its forward end a smoke stack 11, and is supported by any desirable type of

truck 12, to each side of which the lower ends of the cylinder saddle 13 extend.

The truck carries an element presenting a pair of fixed spaced operating fingers 14, 60 which obviously swing with the truck, as the same follows the tracks upon a curve in the rails. The contact fingers 14 co-operate with the outer ends of valve stems 15, the inner end of which extends into a controlling cylinder 16, and with a view of regulating the co-operation of the valve stems, and contact fingers, we preferably employ contact shoes 17 such as have been illustrated in Figure 4, it being noted that these contact shoes are 65 secured to each of the valve stems 15, preferably by means of screw threads, and are held immovable in this position by any suitable means such as lock nuts 18.

Thus the operating cylinder 16 being carried 70 by the cylinder saddle 13 by means of a bracket 19, it will be appreciated that the degree of throw which the contact fingers 14 are capable of imparting to the valve stems 15 may be accurately regulated by means of 75 the contact shoes 17 affixed to the outer end of the latter.

Referring now more particularly to the details of the controlling cylinder it will be seen that the same includes a body portion 85 presenting a preferably centrally located chamber 20, which chamber provides a pair of outlet ducts 21, the flow of fluid through which is controlled by means of the valves 22 affixed to the valve stems 15, and an intake opening 23 in free communication with the chamber 20. The valve stems 15 may 90 preferably mount rings 24 which serve to prevent an accidental displacement of fluid, and beyond these rings 24, the valve stems 95 are each formed with a reduced portion 25 from which grooves 26 or other suitable means extend to a point adjacent the rear of the valve 22, and in line with the outlet duct 21 so that fluid may normally flow from the 100 outlet duct through the grooves 26, reduced portion 25 and exhaust openings 27 of the cylinder.

In normal operation, the fluid utilized will 105 preferably be air, and accordingly the intake opening 23 will communicate through a pipe 28, to an air reservoir (not shown). Also pipes 29 communicate one with each of the outlet openings 21 and serve to communicate one with each end of a controlling cylinder 110 30.

This cylinder is preferably mounted upon

a base 31 which latter rotatably mounts a turn table 32, serving to support a headlight 33 of any desirable type, and a rod 34 has one of its ends slidably secured to a pin 35 attached to the turn table 32, the opposite end of said rod extending through a longitudinal slot 36 in the cylinder 30 and is fixedly secured to a piston 37 slidably mounted within said cylinder.

Now with a view of retaining the piston 37 in its proper position we may provide any suitable means such as adjustable stop pins 38 within the cylinder, which will limit the movement of the piston 37, and to normally retain the piston in the position illustrated in Figure 3, compression springs 39 are arranged between each end of the piston and the heads of the cylinder 30 so that the rod 34 is normally positioned at a point intermediate the extremities of the cylinder, and consequently retains the turn table 32 in a position at which the headlight 33 will be directly in line with the path of straight-way travel on the part of the vehicle.

Assuming however that the vehicle is negotiating a curve it will be obvious that the truck 12 carrying the contact fingers 14 will swing with respect to the cylinder saddle 13, and this will result (according to the curvature of the track) in a more or less pronounced movement of one of the valve stems 15 incident to the contact shoe 17 thereof being engaged by one of the contact fingers aforementioned. This movement will result in a seating of the valve 22 carried by the stem and will obviously permit air from the reservoir to flow through the pipe 28, through the intake opening 23, past the unseated valve and into the corresponding outlet pipe 29. Accordingly air pressure will be admitted to one side of the piston 37 and the latter will be moved to an extent corresponding to the amount of air admitted. This movement will be transmitted to the turn table 32 by means of the rod 34 and the headlight 33 will accordingly be swung to direct its beam to a point at which the path of travel being followed, as well as a great portion of the curve forming a continuation of the same will be illuminated.

Immediately upon the vehicle reaching a straight-way portion of track, or a curve in the opposite direction it will be obvious that the contact finger will move out of engagement with the shoe 17, with which it is co-operating. The air pressure will imme-

diate seat the valve 22 and incident to the fact that the piston 37 is endeavoring to return to its normal, i. e. central position, it will be appreciated that the air pocketed within one end of the cylinder 30 will be permitted to escape, and will flow back through the pipe 29, outlet ducts 21, through the grooves 26, reduced portion 25 and discharge openings 27, thus immediately permitting a return to normal on the part of the turn table.

From the foregoing it will be appreciated that we have constructed a dirigible headlight which, although incorporating the main principle involved in our prior patent aforementioned, presents certain structural improvements thereover, which structure tends to simplify the entire system, reduce the cost of manufacture, and also to add to the efficiency of the device.

It will further be appreciated that our invention is susceptible to a number of different adaptations and that structural modifications of the same may be resorted to without departing from the scope of our claims, which are:

1. A dirigible headlight including means for oscillating a headlight, an operating cylinder for moving said means, said operating cylinder providing a central chamber formed with an intake opening, discharge openings in said operating cylinder, said cylinder being also provided with outlet openings, valves mounted within said cylinder and arranged between said intake and discharge openings, valve stems secured to said valves and projecting beyond the ends of said cylinder, said valve stems being formed with a reduced portion, and grooves normally permitting communication between said outlet openings and the discharge openings forming a part of said cylinder.

2. A dirigible headlight including a rotatably mounted turn-table, said turn-table being adapted to receive a headlight, a cylinder positioned adjacent to said turn-table, a piston slidably mounted within said cylinder, springs interposed between the ends of said piston and the heads of said cylinder, stop pins also extending within said cylinder and limiting the movement of the piston, and means for connecting said piston with said turn-table.

HARRY EXETER BEASLEY.
WALTER BYRD.
